WILLIAM L. BARRON, OF NEW YORK, N. Y., ASSIGNOR TO THE SINGER MANUFACTURING COMPANY, A CORPORATION OF NEW JERSEY.

BUTTON-SEWING MACHINE.

1,151,853.

Specification of Letters Patent. Patented Aug. 31, 1915.

Application filed June 30, 1911. Serial No. 636,173.

To all whom it may concern:

Be it known that I, WILLIAM L. BARRON, a citizen of the United States, residing at New York, in the county of New York and 5 State of New York, have invented certain new and useful Improvements in Button-Sewing Machines, of which the following is a specification, reference being had therein to the accompanying drawings.

10 This invention has for its object to provide effective means for attaching to a fabric integral-shank buttons or those having upon the back of the head a solid shank pressed, molded or otherwise formed there- 15 on and adapted to be penetrated by the needle in applying the fastening stitches; and it has for a further object to provide button-holding means adapted to accommodate interchangeably different sizes and 20 varieties of such type of buttons.

In its preferred form, the improvement is embodied in the jogging work-clamp of a button sewing machine of the well known Singer type, as disclosed in the United 25 States patent to J. J. Sullivan No. 777,564, dated December 13, 1904. As so constructed, the work-clamp comprises a work-supporting plate provided with the usual needle-aperture and constituting the lower 30 member of the work-holder, and the button-holder constituting the upper member of the work-holder, which is carried by a spring-pressed sustaining arm. The button-holder is provided with a button-head cavity ar- 35 ranged in angular relation with the work-supporting plate and afforded by the spaced and reversely inclined extremities of two spring-pressed clamp-arms each carrying a spring-finger for pressing the button-head upon the seat afforded by its respective oper- 40 erative extremity. The work-supporting plate has adjacent that side of the needle-aperture opposite the button-head cavity of the button-holder a work-supporting block 45 whose top is substantially at or slightly above the center of a button-shank extending toward the same between the button-head seats, to permit the fabric to be introduced beneath the button-holder and turned 50 upwardly intermediate the latter and said block and into contact with the end of the button shank, and then over the top of such block upon which it is pressed by means of a presser-foot adjustably secured to the sus- taining arm of the button-holder.

To insure against the clinging of the button to the needle and its premature dislodgment from the holder, a spring-pressed retaining member is mounted upon said sustaining arm with its operative portion normally above the button-head cavity and adjacent the needle-path. Means are provided for retracting this retaining member when the clamp is opened by lifting the button-holder.

In the accompanying drawings, Figure 1 is a perspective view of a button-holding work-clamp constructed in accordance with the present improvement, in connection with a portion of a sewing machine, and Fig. 2 is 70 a front elevation of the same. Fig. 3 is an end elevation of the clamp, showing the lower work-supporting member and the throat-plate in transverse section. Fig. 4 is a perspective view of the button-holder 75 taken from the under side. Fig. 5 is a perspective view of the lower clamp member.

The head 1 of the sewing machine bracket-arm has journaled therein, as usual, the vertically reciprocating needle-bar 2 carrying the needle 3 which constitutes one member of the stitch-forming mechanism, and the spring-pressed bar 4 to whose lower end is secured the block 5 carrying the lateral clamp-lifting pin 6. Resting upon the 80 throat-plate 7 is the flat work-supporting plate 8 forming the lower member of the work-holder and formed with the needle-aperture 9 enlarged to accommodate the heads of the buttons. The plate 8 is pro- 85 vided at the side of the needle-aperture opposite the button-head enlargement with the rectangular block 10 formed in one edge with the needle-clearance notch 11 in register with the adjacent portion of the needle-aperture. The primary work-supporting member 8 is secured by means of a screw- 90 stud 12 and dowel-pins 13 upon the forward end of the slide-bar 14 which carries upon its rearward end the block 15 recessed to 95 receive the downturned rearward end 16 of the upper work-clamp arm 17 pivotally mounted therein, as more fully shown and described in the United States patent to C. M. Horton, No. 1,051,998, of February 4, 100 1913, and having a backwardly offset opposite end portion 18 terminating in the sus- taining plate 19 for the button-holder. In practice the slide-bar may be actuated by 105 any usual or suitable means, such as those 110

represented in the United States patent to J. J. Sullivan, No. 777,564, of December 13, 1904, for producing between it and the stitch-forming mechanism relative lateral jogging movements. Secured by means of the screw 20 upon a suitable seat in the top of the block 15 is the arched pressure spring 21 whose forked forward end rests upon the arm 17 and embraces the stud 22 thereon.

10 Pivottally mounted beneath the plate 19 by means of the fulcrum-studs 23 are the swinging button-clamp levers 24 each provided at the downwardly offset forward end with the transverse button-clamp jaw 25, the 15 adjacent extremities of these jaws being divergently beveled to afford button-head seats 26. Each of the jaws 25 is embraced by a U-shaped spring whose rearward limb 27 is secured thereto by means of the fastening screw 28, while the forward limb 29 rests upon the outer face of the member 25 and overlies the button-head seat 26, so as to produce in conjunction therewith one of the separable parts of the button-head cavity of the button-holder which is disposed 20 in angular relation with the face of the work-supporting plate and parallel with the path of reciprocation of the needle.

The clamp-levers 24 are provided with 30 pending pins 30 entering the divergently arranged cam-slots 31 of a guide-plate 32 secured to the slide-block 33 fitted within the guide-channel 34 in the bottom of the sustaining plate 19 and normally drawn forward to force the button-clamp jaws together by means of the spring 35 having one end attached to the stud-screw 36 passing through the slot 37 of the plate 19 and tapped into the slide-block 33, while the 35 other end of such spring is connected with the post 38 whose hooked upper end 39 extends over the clamp-lifting pin 6. The screw 40, also tapped into the slide-block 33 and working in the guide-slot 37 serves, 40 in conjunction with the stud-screw 36 to retain the slide-block 33 in position.

The normal position of the cam-plate 32 and hence of the button-clamp jaws 25 is determined by means of the stop-lever 41 50 fulcrumed upon the screw-pin 42 and secured adjustably in position by means of the clamp-screw 43, and against which the stud-screw 36 normally rests under the action of the spring 35. The plate 19 has at 55 its forward end the depending lug 19^x to which is fitted the channeled rearward face of the shank 44 of the presser-foot 45 which is adjustably secured in position by means of the fastening screw 47 passing through a 60 slot 46 in said shank. The operative portion of the presser-foot overlies the work-supporting block 10 and is in practice so adjusted that it presses the fabric adjacent the stitching position firmly upon such 65 block.

In the use of the device, the button is inserted from the top into the cavity afforded by the opposed jaws and their confining spring-fingers. To insure against the premature withdrawal of the button from 70 such cavity in the stitching operation, a detaining member is provided which normally overlies the button-cavity but is temporarily retracted for introduction of the buttons. This detaining member comprises a swinging lever fulcrumed upon the stud-screw 48, and is shown herein formed in two parts 49 and 50, the former of which overlies the offset portion 18 of the sustaining arm 17 and is formed with a depending lug 49^x to which 75 is adjustably secured by means of the screw 51 entering the elongated slot 52 therein the channeled and upturned rearward end portion 53 of the part 50 whose forward portion is bent laterally to bring its operative extremity 54 into register with the button-head cavity of the holder. The part 49 of the detaining lever carries a pin 55 to which is connected one end of a spring 56 having its opposite end attached to the post 38 by 80 means of which the lever is maintained normally in operative position in which its edge rests against the stop-pin 57 upon the arm 18. Secured to the bracket-arm head 1 by means of the screw 58 is a rigid depending arm 59 having at its lower end the laterally inclined cam edge 60 disposed slightly above the inner edge of the lever section 49 and slightly in advance of the arm 18. The lifting of the arm 18 with the 85 button-holder brings the detaining lever into engagement with the cam-edge 60 and causes the retraction of the operative extremity thereof from normal relation with the button-cavity. 90

The manner of using the improvement 95 will be seen by reference more particularly to Fig. 3. The raising of the lifting bar 4 by the usual means causes the engagement of the pin 6 with the post 38 and the consequent raising of the sustaining plate 19 of the button-holder, whereby the latter is lifted 100 from the work-supporting plate 8 and the button-detainer is retracted, as represented in Figs. 1 and 2. The button is then 105 introduced into the button-cavity from the top with the back of its head *b* in contact with the inclined seats 26 of the jaws 25, the front or upper side of its head pressed inwardly by the spring-fingers 29, and the shank *b'* extended between the jaws 25 to 110 expose its transverse aperture *b*² for passage of the needle in its outer thrust. The material *m* is then placed upon the supporting plate 8 with the portion to receive 115 the button-attaching stitches adjacent the forward edge of the block 10, after which the button-holder is lowered, whereby the lower edge of the button forces the underlying material partly through the enlarge- 120 125 130

ment of the needle-aperture 9 of the plate 8 and into the clearance recess 7^x of the throat-plate beneath the same, and the button-shank bends the material over the forward 5 edge of the block 10 and into contact with its adjacent extremity. The lowering of the clamp serves to disengage the detaining lever from its retracting cam 60 and permits it to assume operative relation with the 10 button-holder wherein its extremity 54 overlies the button-cavity and rests in contact with the upper edge of the button.

The operation of the machine now proceeds, the relative jogging movements between 15 the needle and the work-clamp effecting the descent of the needle alternately through the button-shank aperture and the material adjacent the end of the button-shank, whereby a series of fastening stitches 20 s is produced by which the end of the button-shank is bound closely to the face of the material, the height of the top of the work-supporting block 10 relative to the upper side of the button-shank determining 25 the amount of play of the button upon the fastening stitches and the degree of flexibility of the button fastening. As will be seen by reference more particularly to Fig. 5, the needle-aperture of the work-support 30 is formed partly in the body of the plate 8 and partly in the front face of the block 10 which affords the deflecting shoulder for the material to sustain the latter in contact with the end of the button-shank. 35 This position of the needle-aperture is required to permit the needle-punctures to be applied to the material alternately above and below that portion lying along the face of the block 10 parallel with the path of 40 reciprocation of the needle.

The machine to which the present work-holder is applied is provided beneath the throat-plate with thread-cutting mechanism for severing the fastening threads 45 after each button-fastening operation, and the loose ends of thread left after each stitching operation therefore remain upon the under side of the work. As, according to the present improvement, the button 50 is clamped within its holder entirely independent of the fabric to which it is to be attached, it will be seen that the character of the fabric and its thickness do not affect the positioning of the button-shank relatively to the needle. This is a matter of importance, for the reason that, especially in pressed or molded integral-shank buttons the thread-aperture in the shank is comparatively small and must be located with precision relative to the needle-path in order to prevent the breaking of either the needle or the button by reason of imperfect register of the one with the other.

As the fulcrum-studs 23 for the button-clamping arms 24 are sustained in fixed re-

lation to the work-holder, they serve to determine positively the position of the button-head seat 26 relative to the inner and outer paths of reciprocation of the needle, but the resilience of the spring-fingers 29 70 adapts the button-head cavity to yield in depth for accommodation of button-heads of different thicknesses and the adjustment of the stop-lever 41 serves to determine the initial spacing of the jaws to accommodate 75 button-heads of different diameters. The yielding character of the button-head cavity, while fixing with precision the initial position of the button-shank relative to the needle, permits the slight movement thereon of the button to compensate for the crowding of the needle from one side or the other of the button-shank aperture by reason of its partial filling by the fastening threads in the course of a stitching operation. In practice, it has been found that the breakage of needles has been greatly reduced by the employment of the yielding fingers 29 permitting the button to accommodate itself to the needle under the conditions referred to. 85

While the various constructive features herein shown and described obviously contribute to the effectiveness of the button-holder, it is evident that certain of them 95 are susceptible of modification or may be wholly omitted from association with others without departure from the present invention.

Having thus set forth the nature of the 100 invention, what I claim herein is:—

1. Work-holding means comprising a work-supporting member having a work-sustaining operative face provided with a shoulder in angular relation therewith, and 105 a button-holding member constructed with a pair of reciprocally movable levers provided with jaws adapted to yieldingly engage a button-head at opposite sides of its shank aperture and sustained by and movable with their respective levers in a path substantially parallel with the face of said shoulder, means connected with said jaws for pressing them toward each other, and means carried by and adapted to frictionally 110 maintain a button in engagement with said jaws.

2. Work-holding means comprising a work-supporting member having a work-sustaining operative face provided with a shoulder in angular relation therewith, and a button-holding member constructed with a support, a pair of jaws mounted upon said support and disposed at the side of and rigidly sustained at a fixed distance from the face of said shoulder, means connected with said jaws for pressing them toward each other, and a spring-finger carried by 115 each of said jaws for frictionally maintaining the button in engagement therewith. 120

3. Work-holding means comprising a work-supporting member having a work-sustaining operative face provided with a shoulder in angular relation therewith, and a button-holding member constructed with a support, a pair of reciprocally movable jaws upon said support and confined to movement in a path substantially parallel with the face of said shoulder, spring-actuated means including an adjustable stop for yieldingly maintaining said jaws a fixed distance apart, and yieldingly acting means for holding a button-head in engagement with said jaws with its shank projecting between the same.

4. Work-holding means comprising a work-supporting member having a work-sustaining operative face, and a button-holding member constructed with a support, a pair of opposed and reciprocally movable levers mounted upon said support and provided with laterally spaced jaws having vertical button-head engaging faces in angular relation with the operative face of the work-supporting member, means connected with said jaws for pressing them toward each other, and means carried by said levers for yieldingly holding a button-head in engagement with said jaws with its shank projecting between the same.

5. In a button-sewing machine, the combination with stitch-forming mechanism including a reciprocating needle, of a work-support provided with a shoulder in angular relation with and extending above the operative face of the same and with a needle-aperture, and a button-holder constructed with separable jaws affording a seat for the button-head sustained at a fixed distance from the range of movement of the needle

and spring-fingers each carried by one of said jaws and each overhanging its respective portion of the button-head seat, thereby producing a yielding button-head cavity.

6. In a button-sewing machine, the combination with stitch-forming mechanism including a reciprocating needle, of a work-support provided with a shoulder in angular relation with and extending above the operative face of the same and with a needle-aperture formed partly in the body of the work-support and partly in the face of said shoulder, and a button-holder constructed with separable jaws affording a seat for the button-head sustained at a fixed distance from the range of movement of the needle and spring-fingers each carried by one of said jaws and each overhanging its respective portion of the button-head seat, thereby producing a yielding button-head cavity.

7. In a button-sewing machine, the combination with stitch-forming mechanism including a reciprocating needle, of a work-support, a button-holder movable bodily toward and from the work-support and provided with an open-topped button-head cavity arranged transversely to the work-support, a button-detainer laterally movable toward and from operative position above said button-cavity, and common means for simultaneously lifting the button-holder and retracting the button-detainer from operative relation therewith.

In testimony whereof, I have signed my name to this specification, in the presence of two subscribing witnesses.

WILLIAM L. BARRON.
